UNITED STATES PATENT OFFICE.

ALVIN H. SHOEMAKER, OF SEATTLE, WASHINGTON, ASSIGNOR OF ONE-HALF TO WILLIAM I. EWART, OF SEATTLE, WASHINGTON.

RAIL-JOINT.

No. 906,072.

Specification of Letters Patent.

Patented Dec. 8, 1908.

Application filed October 17, 1907. Serial No. 397,839.

To all whom it may concern:

Be it known that I, ALVIN H. SHOEMAKER, a citizen of the United States, residing at Seattle, in the county of King and State of Washington, have invented certain new and useful Improvements in Rail-Joints, of which the following is a specification, reference being had therein to the accompanying drawings.

10 This invention relates to rail-joints.

The principal object of the invention is the provision of a joint that will retain the rail-ends in alinement, and whereby the stresses received from a moving train will be distributed throughout the joint structure and thus relieve the track itself as well as the bolt fastenings of the joint from the severe duty to which a track-rail is subjected.

With these objects in view, the invention 20 consists in the novel construction, adaptation and combination of fish-plates and chairs with the standard type of track-rails, as will be hereinafter described and claimed.

In the drawings, Figure 1 is a side elevation of an embodiment of my invention with portions broken away and illustrating its adaptation to rails and ties of ordinary construction; and Fig. 2 is a transverse cross sectional view of the same.

30 Referring to the drawings, the reference numeral 5 indicates a base or chair which is of sufficient length to be supported by at least two ties 6. It is constructed of cast-steel, or other suitable metal, and is comprised of a plate having, adjacent to its longitudinal edges, upwardly extending ridges 8 which are respectively provided with inner concave faces 8'.

9 are angle fish-plates adapted to be secured to the rails 10, as by bolts 11 passing through the holes 12 and 13 in the plates and rails, respectively. Said angle-plates are formed with oppositely inclined faces 14 and

15 adapted to interfit with correspondingly inclined faces 10' and 10'' of the rail head and foot, respectively. The laterally projecting flange 9' of an angle-plate, for strength and rigidity, is formed relatively thick and is turned downwardly along its outer edge to 50 extend below the bottom 10''' of the rail-

foot and terminates in a toe 9'' adapted to fit with the face 8' of the base.

In practice, the base 5 is placed upon the track-ties to which it is secured by spikes 7, or an equivalent. The angle-plates 9 are 55 supported upon the base and, in turn, support the ends of the rail 10 and in such manner that the rails are sustained so that the foot thereof will not contact with the chair. In consequence of this manner of assemblage, 60 it is evident that the weight of the track-rail and the loads thereupon are not imparted directly to the chair, but are transmitted to the latter through the angle-plates, thereby putting a constant, though varying, strain 65 upon the angle-plates which insures that the component joint parts will always be effective without depending upon securing bolts other than is necessary to retain the angle-plates in close relation with the rails. 70 In other words, the angle-plates form what, for illustration, may be deemed the sides of a triangle, while the chair forms the base and also serves to prevent the spreading of the lower portions of the plates in opposition to 75 the downward and lateral forces applied to their tops from the rail-head.

Having described my invention, what I claim, is—

1. A rail joint consisting in combination 80 with the rails, of a base member provided in proximity of its lateral edges with upwardly directed ridges having concave inner faces, rail bearing angle plates having convex outer edges to fit in said concave faces of the ridges 85 and having their upper edges inclined to engage and fit with the inclined underneath face of the rail treads and supporting the rails so that the base of the same will be some distance above the top of said base member, 90 the base of said convex outer edges of the angle plates being free from contact with the base member.

2. A rail joint comprising in combination 95 with the rails, a base member provided in proximity of its lateral edges with upwardly extending ridges provided with concave inner faces, rail bearing angle plates having laterally-projecting depending flanges provided with convex outer faces fitting the con- 100

cave inner faces of the ridges, the base of said depending flanges being free from contact with the base member, and the upper edges of said angle plates fitting with and engaging 5 the underneath faces of the rail treads so that the rail base is held suspended above the base member throughout the length of the latter by the engagement of the angle plates at their upper edges with the rail

treads and the engagement of the outer faces 10 of the laterally-depending flanges with the concave inner faces of the ridges.

In testimony whereof I affix my signature in presence of two witnesses.

ALVIN H. SHOEMAKER.
